FIG. 1 is a front perspective view of the flat panel display mount;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a second front perspective view thereof shown in an alternate position.

The broken lines shown on the drawings are included for the purpose of illustration and form no part of the claimed design.
